CIRCUIT-INTERRUPTER.

1,313,856.

Specification of Letters Patent. Patented Aug. 19, 1919.

Application filed November 15, 1918. Serial No. 262,641.

To all whom it may concern:

Be it known that I, JOHN F. CAVANAGH, a citizen of the United States of America, residing at Meriden, Connecticut, have invented a new and useful Circuit-Interrupter, of which the following is a specification.

My present invention relates to the timing mechanism for internal combustion engines and the objects of the invention are to provide a simple and effective circuit interrupter construction which will be capable of high speed operation and which will retain its sufficiency even after long use.

The circuit interrupters now employed in distributor ignition systems have certain objections in common, some of the most serious of which, are the melting and oxidizing of the interrupter points which results in "pitting" and arcing, causing imperfect contact and the introduction of resistance in the primary circuit etc. Other faults arise from the fact that the interrupter points must be kept free of grease and oil, while the cam mechanism for vibrating the contacts should on the other hand, be well lubricated. These opposed requirements usually result in the insufficient lubrication of the mechanical vibrating mechanism and the consequent rapid wearing of these parts.

Another disadvantage of the prior art devices, is the frequent necessity for adjustment of the interrupter contacts to take up for the wear and the burning away of the contact points, which adjustments usually result in the contact points being put out of parallelism, which results in further uneven wear of the points.

In my invention I have avoided the objections mentioned and have provided a circuit interrupter which has proved satisfactory in every respect by inclosing the interrupter contacts within a compartment and by effecting the vibrations of the contacts through the medium of a flexible diaphragm forming one of the walls of said compartments.

For the purposes of disclosure I have shown the invention in the accompanying drawing embodied in several different forms, but I would have it understood that the invention may be embodied in other and

still different forms without departure from the true spirit and scope of the invention as defined in the appended claims.

In this drawing:—

Figure 1, is a cross sectional view of a circuit interrupter designed for a four-cylinder combustion engine.

Fig. 2, is a plan view of the same.

Figs. 3 and 4 are sectional views of two other forms of the invention.

The interrupter contacts or "points" as they have been termed, are in the drawing designated 5 and 6 and are shown furthermore as of ring construction to provide annular contacting faces, the central portion of such contacts being shown as hollowed out or reduced as indicated at 7, so as to cause the contacts to engage at their rims only.

The contact 5 as shown, is mounted in a relatively stationary support 8 of cupped construction to provide an open chamber and the coöperating contact 6 is shown as directly carried by a flexible diaphragm 9 closing the open side of the chamber and providing, with the support, a sealed chamber 10 for the "break" or "gap" between the contacts.

The diaphragm 9 is usually constructed of spring material such as bronze or steel and tensioned so as to hold the contacts normally in engagement. In the illustration the diaphragm is clamped at its edges under the necessary tension by a ring 11 which may be spun over the metal of the cup-shaped support. The diaphragm is furthermore shown as insulated from the support by a suitable medium such as the insulating washer 12 interposed between the body of the support and the clamping ring.

The means for vibrating or flexing the diaphragm in a circuit open direction, consists in the present disclosure of a cam 13 having suitable connection with the diaphragm. In the first form, the operating connections consists of a lever 14 having a spring mounting 15 and connected with the diaphragm by extending the shank 16 of the upper contact loosely up through an opening 17 in the lever and flanging it over at 18 to provide a shoulder for engagement by

the lever as the lever is lifted by the cam points. The lever is shown provided with a wear-piece 19 for engagement with the cam points, as customary in structures of 5 this character. The spring mounting for the lever is shown provided by forming a bend in the lever near the end thereof, the lever being supported for instance, by securing it directly to the base or support 8, 10 as indicated at 20.

From the foregoing it will be clear that as the spring lever is lifted by the cam points, it will "pick up" the diaphragm through the connections described and thus periodically effect a separation of the interrupter contacts. As the break between the contacts is located entirely within the closed chamber, the oxidation is negligible. To absolutely eliminate oxidation the chamber may be exhausted more or less and in some instances I 20 find it desirable to introduce an inert gas such as nitrogen into the chamber. Working in this inclosed space, free from dust and other influences, the extent of separation between the contact points may be very slight and this enables the interrupter being operated at very high speed. The diaphragm maintains the movable contact in absolute parallelism with the relatively stationary 25 contact and this, with the annular construction of the contacts produces practically perfect contact between the points and avoids resistance losses, wearing, etc. The lost motion connection described between the 30 diaphragm and the operating means therefore, enables the separation of the contacts in parallel planes and further enables the relatively movable contact to seat itself firmly against the fixed contact under the 35 tension of the spring diaphragm.

In the modification illustrated in Fig. 3, the construction of the contacts is varied to the extent of mounting the lower contact on a screw post 21 having an adjustable engagement in the screw seat 22 in the base or support 8, said lower contact being in the form of a flat head 23 engaged at its rim by the upstanding rim portion 24 of the annular contact 25 carried by the diaphragm. 40 In this case, the cam makes direct engagement with the diaphragm which, for the purpose, is provided with a wearing-piece 26 for engagement by the cam points.

It will be obvious that in the rotation of 45 the cam, the points thereon will depress the diaphragm and thereby effect a separation of the annular contact elements within the sealed chamber. This construction makes it possible to relatively adjust the contacts, 50 by turning the screw post of the lower contact without unsealing the chamber.

The construction illustrated in Fig. 4 is generally similar to the first form described, except that in this case the cam operates

upon the diaphragm through the medium of 55 an insulating push button 27 working through an opening 28 in the supporting base 8 and engaging at its upper end with the diaphragm-carried contact. This push button is shown mounted on a flexible dia- 70 phragm 29 secured to the support and forming the rear wall of the sealed chamber, said button having a suitable wearing head 30 for engagement by the cam points. In the operation of this form the contact-carrying 75 diaphragm is pushed upward from the under side thereof instead of being lifted from the upper side, as in the first form.

The diaphragm, being imperforate, excludes dust and oil and permits lubrication 80 of the cam mechanism to any extent required. The cam in fact may be operated in a continuous bath of oil or grease, reducing the wear at this point to a practically negligible extent. If oxygen is present in the 85 chamber when the contacts are sealed, this is quickly consumed and the contacts thereafter operate in a substantially neutral atmosphere. Another advantage arising from the use of the diaphragm is that any heat 90 generated is quickly dissipated by the relatively wide expanse of thin metal presented by the diaphragm.

I claim:—

1. In a circuit interrupter, the combination of relatively separable contacts, a flexible spring diaphragm tensioned to hold said relatively movable contacts in engagement and means for flexing said diaphragm to accomplish the separation of said contacts. 95

2. In a circuit interrupter, the combination of relatively movable contacts, a spring diaphragm supporting one of said contacts and tensioned to hold the contacts normally engaged and means for periodically flexing 105 the diaphragm to separate the contact carried thereby from the coöperating contact.

3. In a circuit interrupter, the combination with a support having a chamber, a spring diaphragm sealing said chamber, co-operating interrupter contacts carried by 110 the support and diaphragm respectively, said diaphragm being tensioned to normally hold the contacts engaged, and means for effecting the periodic flexure of said dia- 115 phragm.

4. In a circuit interrupter, the combination with chambered means having a flexible diaphragm for one wall thereof, annular interrupter contacts engaging only at their 120 rim portions and located within the chamber aforesaid, one of said annular contacts being carried by the flexible diaphragm so as to conduct heat thereto and so as to be operated thereby, and means for flexing the 125 diaphragm.

5. In a circuit interrupter, the combination with relatively separable contacts and

a flexible diaphragm supporting one of said contacts, of means for periodically vibrating said diaphragm and a lost motion connection between said vibrating means and the diaphragm.

6. In a circuit interrupter, the combination with relatively separable contacts and

a flexible diaphragm for operating the same, of means for periodically vibrating said diaphragm and a lost motion connection between said vibrating means and the diaphragm. 10

JOHN F. CAVANAGH.
